UNITED STATES PATENT OFFICE.

DAVID RENSHAW, OF BRAINTREE, MASSACHUSETTS.

INJECTOR.

SPECIFICATION forming part of Letters Patent No. 274,968, dated April 3, 1883.

Application filed January 20, 1883. (No model.)

To all whom it may concern:

Be it known that I, DAVID RENSHAW, of Braintree, in the county of Norfolk and State of Massachusetts, have invented certain new and useful Improvements in Injectors; and I do hereby declare that the following is a full, clear, and exact description of the invention, which will enable others skilled in the art to which it appertains to make and use the same, reference being had to the accompanying drawings, and to the letters of reference marked thereon, which form part of this specification.

This invention relates to injectors for the propulsion of steam, gases, or air, its object being to enable the rapid transference of large volumes of gaseous or aeriform fluids by the aid of steam-currents.

With these ends in view the invention consists, mainly, in a novel combination, with the steam-supply pipe and the transfer conduit or conduits for supplying the gas or fluid to be transferred, of a multitubular steam-receiver and an enlarged condensing-chamber, which connects preferably directly with the discharge-pipe, so that, the steam entering said condensing-chamber in a multiplicity of jets, its rapid condensation will be insured.

It also consists in the combination, in an injector, with a multitubular steam-receiver, of a series of supply-inlets surrounding the same, so that the gas or fluid to be transferred will surround and enter between and among the tubes and flow along the same to their discharge ends, whereby its mingling with and condensation of the steam are facilitated.

The invention further consists in the combination, with the condensing-chamber, supply devices, and multitubular steam-receiver, of a water-spray nozzle arranged to force a spray of water into the condensing-chamber, for the purpose of facilitating the forming of a vacuum therein.

In the accompanying drawings, Figure 1 is a longitudinal section of an injector constructed according to my invention. Fig. 2 is a similar section, showing the injector provided with a water-spray nozzle. Fig. 3 is a cross-section of the injector in a plane indicated by the line xx of Fig. 1. Fig. 4 is a similar section on the line yy of Fig. 2.

Referring to Figs. 1 and 3, the letter A indi-

cates the inclosing-cylinder, which is enlarged at one end to form the condensing-chamber B, which is contracted at its outer end to join the discharge-pipe C, provided with a check-valve at D. At its rear or outer end of the cylinder A is a steam-chamber, E, separated from the main portion by a partition, f, in which are set in annular rows the tubes G, communicating with the steam-chamber and increasing in length toward the center of the cylinder.

Surrounding the cylinder and the inclosed tubes G is a passage, H, communicating with the interior of the cylinder by a circumferential series of apertures, i, and connected with the gas or air transfer pipe K.

L is the main steam-supply pipe, which is connected with the steam-chamber B and provided with a stop-cock, M. The steam-chamber is provided with a draw-off cock, n, for the escape of condensed water, and in the casing of the check-valve is a vent closed by a plug, p, which may be removed to permit the escape of air from the condensing-chamber.

The operation of the injector, as shown in Fig. 1, is as follows: The transfer-pipe K is to be connected to a reservoir or container from which gas, steam, or air is to be transferred, and the discharge-pipe C is to be connected with the receptacle to which the said gas, steam, or air is to be supplied; or it may be left open to the air if it is merely intended to exhaust the gas, steam, or air from a given point. When it is desired to start the injector into operation, the plug p is removed and the cock M in the steam-pipe is turned slightly to supply a small quantity of steam to the steam-chamber, from which it flows through the tubes G to the condensing-chamber, driving the air therefrom, partly becoming condensed, and a portion being forced through the vent in the check-valve casing. The condensation in the chamber B causes a vacuum therein, which also extends into the transfer-pipe K, and causes gas, air, or other fluid to be drawn through the same and the apertures i until the condensing-chamber is filled. When "solid" water flows from the vent, the plug p is to be replaced and the cock M fully opened to turn on a full supply of steam, which is rapidly condensed by the water in the chamber B and issuing from pipes G, the water at the same time being

heated and driven past the check-valve and through the discharge-pipe C, tending to create behind it a vacuum, assisted by further condensation of steam, which lifts a continuing supply of the gas or similar fluid through its transfer-pipe to the chamber B as long as the steam-cock M is kept open. The subdivision of the steam into small jets by the multitubular receiver and the provision made for the entry of the moving gas among the tubes and at their discharge ends insure a complete condensation and efficient vacuum.

In the modified construction of the injector illustrated in Fig. 2 it is provided with a water-spray nozzle or rose-head carried by a pipe, r, which is arranged through the steam-chamber and the center of the cylinder, said nozzle standing in advance of the tubes G, so that its spray will have free access to the condensing-chamber. By using this nozzle I secure a more speedy starting of the injector into operation. In starting, instead of first turning on a partial supply of steam at the cock M, I turn on a full supply through pipe r, and the steam, issuing therefrom through the finely-perforated rose Q in the form of a steam-spray, is very rapidly condensed, and a lifting vacuum is speedily created. When steam is to be transferred, the water-spray may be continued in operation during the whole time for the purpose of assisting the cooler steam, which is to be transferred in condensing the injecting steam.

Having now described my invention and explained the principle and operation thereof, I wish it to be understood that I do not confine myself to the precise arrangement and construction of parts shown in the drawings and heretofore particularly described, but may vary them in any manner tending to more efficiently carry out the principle of my invention without departing from its true scope and spirit. I wish it also to be understood that I do not

confine myself to the use of my injector for transferring gaseous or aeriform fluids, as it may be used for supplying feed-water to steam-boilers, the transfer-pipe K serving in such case as the water-supply pipe and the discharge-pipe C as the feed-pipe.

What I claim is—

1. In an injector, the combination, with the steam and transfer pipes, of the multitubular steam-receiver, the tubes arranged to form a cone, as shown, and condensing-chamber, substantially as described.

2. The combination, with the multitubular steam-receiver, of the series of water-inlets surrounding the same, substantially as described.

3. The combination, with the condensing-chamber, transfer-conduits, and multitubular steam-receiver, of the air or water spray nozzle, arranged in advance of the steam-receiver pipes, substantially as described.

4. In an injector, the combination, with the multitubular steam-receiver, the tubes arranged to form a cone, as shown, and a central rose-head, of the steam-chamber E, communicating with the tubes thereof, substantially as described.

5. The injector consisting of the cylinder A, having steam-chamber E and enlarged condensing-chamber B, the multitubular steam-receiver, the tubes of which communicate with said steam-chamber, and the passage H, surrounding the cylinder and having communication therewith through a circumferential series of inlets, substantially as described.

In testimony that I claim the foregoing as my own invention I affix my signature in presence of two witnesses.

DAVID RENSHAW.
